(57) **CLAIM**

The ornamental design for a leveling device, as shown and described.

DESCRIPTION

FIG. 1 depicts an upper perspective view of the leveling device, in a compact configuration.

FIG. 2 depicts a top plan view of the leveling device of FIG. 1.

FIG. 3 depicts a bottom plan view of the leveling device.

FIG. 4 depicts a lower perspective view of the leveling device.

FIG. 5 depicts a first side elevation view of the leveling device.

FIG. 6 depicts a second side elevation view of the leveling device.

FIG. 7 depicts a front side elevation view of the leveling device.

FIG. 8 depicts a rear side elevation view of the leveling device.

FIG. 9 depicts an upper perspective view of the leveling device, in an extended configuration.

FIG. 10 depicts a top plan view of the leveling device of FIG. 9.

FIG. 11 depicts a bottom plan view of the leveling device of FIG. 9.

FIG. 12 depicts a lower perspective view of the leveling device of FIG. 9.

FIG. 13 depicts a first side elevation view of the leveling device of FIG. 9.

FIG. 14 depicts a second side elevation view of the leveling device of FIG. 9.

FIG. 15 depicts a front side elevation view of the leveling device of FIG. 9; and,

FIG. 16 depicts a rear side elevation view of the leveling device of FIG. 9.
